UNITED STATES PATENT OFFICE.

HENRY DUENNER, OF BOSTON, MASSACHUSETTS, ASSIGNOR OF ONE-HALF
TO FREDERICK BLEILER, OF SAME PLACE.

COMMUTATOR FOR ELECTRIC MOTORS.

SPECIFICATION forming part of Letters Patent No. 449,774, dated April 7, 1891.

Application filed October 16, 1890. Serial No. 368,252. (No model.)

To all whom it may concern:

Be it known that I, HENRY DUENNER, residing in Boston, in the county of Suffolk and State of Massachusetts, a subject of William, Emperor of Germany, have invented 5 certain new and useful Improvements in Commutators for Electric Motors, of which the following is the specification.

It is well known that the brushes which are applied to the periphery of the commutator-cylinder require to be shifted endwise of the cylinder from time to time in order to prevent the cylinder from wearing in circumferential grooves. This is usually done by loosening 10 the nuts which hold the brushes to the spindle on which they are mounted and moving them endwise of the spindle and then fastening the nuts in a new place.

My improvement consists in mounting the brushes upon a spindle which is movable longitudinally and applying thereto cross-head slides and an adjusting-screw so that by a single turn of the screw the brushes may be adjusted longitudinally. This makes it 15 much more convenient, and is economical of time.

In the drawings, Figure 1 is a plan of the improved apparatus as I have arranged it. Fig. 2 is a longitudinal section through the 20 center of one of the brush-carrying spindles. Fig. 3 is a detail, partly in plan and partly in elevation, of a portion of the improved apparatus. The last two figures are on a larger scale than the scale of Fig. 1.

35 In the drawings, A indicates the commutator. The armature to which this commutator is attached and from which it derives its electricity is not shown.

B is the frame, which carries the brush-spindles, and which supports them in their relation to the commutator.

40 G is an insulating-collar, which insulates the commutator from the frame. This collar has a neck which enters the frame and surrounds the commutator-shaft. This neck being concealed within the box is not represented in the drawings, and F is a spindle or shaft forming part of the axis of the commutator.

45 C are the brushes formed, as usual, out of strips of metal. They are mounted, as shown in Fig. 2, in the blocks H, and are adjustable

55 to and from the commutator on loosening the set-screws Q, and, when adjusted, these screws may be tightened again. These blocks H are mounted on a spindle D, which is at present usually fixed to the frame B. A usual way of applying these blocks H is shown in Fig. 3, where they are spaced from each other and allowed a little elasticity from the fact that they are fastened to the shaft D by a collar 60 which has a gland something like the gland of a stuffing-box, which enters into a cavity in the box H and there compresses a spring contained in the same cavity. These collars are fastened to the shaft by means of 65 set-screws I. (Shown in the drawings, Fig. 3.) In the device which I have contrived this spindle passes through the frame B, and is not attached to said frame, but fits in it, so that it may be slid in and out, as desired. 70 The handle P may be arranged to clamp this shaft in position when it has been set, if desired, or a set-screw S may be employed for that purpose. I have added parts to the ordinary construction for each set of brushes. 75

80 A pair of ways L, (shown in plan in Fig. 1 and in section in Fig. 2,) which ways at their outer end are united by a perforated yoke T, as shown in Fig. 2, project from the frame. These ways are formed so that an insulating 85 cross-head or slide may be moved freely in them longitudinally of the ways. To this cross-head (marked K) is attached the spindle D, which is in conducting-connection with the binding-post E, from which the conducting-wires are laid. The ways L are insulated 90 from the frame B. There is no conducting relation between the spindle D and the ways nor between the spindle D and the adjusting-screw. The insulating cross-head is shown 95 in Fig. 2 as composed very largely of insulating material and in Fig. 3 as composed of insulating material with a conductor embedded in it leading to the binding-post E; but it is obvious that it is not requisite to make the cross-head entirely of insulating material. Insulating material, must, however, be interposed between the spindle D and the adjusting-screw m, and also between the adjusting-screw m and the conductor, which leads from 100 the spindle D to the binding-post E. There is mounted in the yoke T at the end of the

ways an adjusting-screw m , which has a collar n and a shouldered milled head O for laying hold of it. This adjusting-screw m lays hold of the cross-head and moves it and the spindle attached to it to and fro longitudinally of the ways.

It is obvious that any form of insulation that shall insulate the spindle D from the milled head O will practically suffice for the work of this apparatus, although it would undoubtedly be better to have the ways insulated from the spindle D , and also the adjusting-screw m insulated from the spindle D by suitable blocks of insulating material.

I claim as my invention and desire to secure by Letters Patent of the United States—

1. The combination, in a commutator for dynamo-electric machines, of the brushes C

with the longitudinally movable spindle D , the ways L , cross-head K , and adjusting-screw m , said spindle being insulated from the ways and from the adjusting-screw, substantially as described.

2. In a dynamo-electric machine, the combination of a longitudinally-movable brush-carrying spindle D with a pair of ways insulated from said spindle and from the adjusting-screw m , and with a cross-head carrying a binding-post insulated from the ways and the adjusting-screw, and in conducting relations with the spindle D , substantially as and for the purposes described.

HENRY DUENNER.
